J. H. DOWNS.

INTERNAL COMBUSTION ENGINE.

APPLICATION FILED APR. 12, 1918.

1,315,290.

Patented Sept. 9, 1919.

UNITED STATES PATENT OFFICE.

JOSEPH H. DOWNS, OF WOODBURN, INDIANA.

INTERNAL-COMBUSTION ENGINE.

1,315,290.

Specification of Letters Patent. Patented Sept. 9, 1919.

Application filed April 12, 1918. Serial No. 228,201.

To all whom it may concern:

Be it known that I, JOSEPH H. DOWNS, a citizen of the United States, residing at Woodburn, in the county of Allen, State of Indiana, have invented a new and useful Internal-Combustion Engine; and I do hereby declare the following to be a full, clear, and exact description of the invention, such as will enable others skilled in the art to which it appertains to make and use the same.

The present invention relates to a double acting four cycle internal combustion engine, and has for its object to provide an engine of this character which embodies novel features of construction whereby each of the pistons will receive a power impulse for every revolution of the crank shaft, and in which the pistons will be accurately guided in their reciprocating movements so as to prevent leakage of the gases and side wear upon the pistons and cylinders.

Further objects of the invention are to provide an engine of this character which is simple and compact in its construction, which provides for thoroughly scavenging the cylinders of burned gases, and which is positive and reliable in its action.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawings, in which:

Figure 1 is a side elevation of an internal combustion engine constructed in accordance with the invention, one-half thereof being broken away and shown in section to illustrate more clearly the details of construction.

Fig. 2 is a transverse sectional view through the engine.

Fig. 3 is a top plan view of one end of the engine.

Fig. 4 is an enlarged horizontal sectional view through one of the cylinders, looking downwardly, and

Fig. 5 is an enlarged detail view of the lower end of one of the piston rods and the tubular guide member for the same, showing the small expandible packing rings which are fitted upon the piston rod.

Corresponding and like parts are referred

to in the following description and indicated in all the views of the drawings by the same reference characters.

For the purpose of illustration, the invention is shown as embodied in a six-cylinder engine, although it will be obvious that the number of cylinders may be increased or decreased, as desired. The numeral 1 designates the cylinder casting which is preferably formed as an integral part, and is shown as formed with the six cylinders A, B, C, D, E and F. Upper and lower cylinder heads 2 and 3 respectively are applied to the cylinder casting 1 and rigidly secured in position in any suitable manner as by means of the bolts 4. Pistons 5 are mounted to reciprocate within the respective cylinders, being provided with piston rods 6 which extend downwardly through tubular guides 7 applied to the lower cylinder head 3, and being operatively connected at their lower ends to the crank shaft 8 by means of connecting rods 9. This crank shaft is of the conventional construction, being journaled within suitable bearings 10 and housed within a conventional crank case 11. A fly wheel 12 is shown as applied to one end of the crank shaft.

The upper cylinder head 2 is shown as provided upon opposite sides thereof with inlet passages 13 and exhaust passages 14, said passages each communicating with the corresponding engine cylinder through a pair of ports which are controlled by puppet valves. The two inlet valves 15 are formed with valve stems 16 which extend upwardly through the cylinder head and terminate in heads 17, springs 18 being interposed between the heads and top of the engine and operating to normally hold the valves in a closed position. In a similar manner the two exhaust valves 19 are each formed with stems 20 which extend upwardly through the cylinder head and terminate in heads 21 which are engaged by the springs 22, said springs normally holding the valves in a closed position. Rocker arms 23 are provided for opening the exhaust valves 19, while similar but shorter rocker arms 24 are provided for opening the inlet valves 15, said rocker arms being pivoted at 25 in a superposed relation upon upstanding brackets 26. The outer ends of these rocker arms are connected to vertical push rods 27 which extend downwardly into the crank case, being directed in their up and down move-

ments by the guide sleeves 28, and being actuated at the proper intervals of time by a cam shaft 29.

The lower cylinder head has a construction similar to that of the upper cylinder head, being provided with inlet passages 30 and exhaust passages 31 which open through opposite sides thereof, said passages each communicating with the bottom of the 10 respective engine cylinder through a pair of ports. Puppet valves 32 control the inlet ports, while puppet valves 33 control the exhaust ports. The valves 32 are formed with stems 34 which extend downwardly 15 through the cylinder head and terminate in a head 35, springs 36 being interposed between the engine and the head and normally serving to hold the valves in a closed position. In a similar manner the exhaust 20 valves 33 are provided with stems 37 which extend downwardly through the cylinder head and terminate in heads 38 which are engaged by springs 39, said springs normally tending to hold the valves in a closed position. 25 Rocker arms 40 are provided for opening the inlet valves, while shorter but similar rocker arms 41 are provided for opening the exhaust valves, said rocker arms being pivoted at 42 in a superposed relation upon brackets 43 which project downwardly from the lower cylinder head. The free ends of the rocker arms are connected to pull rods 44 which slide vertically through guides 45, being provided at their lower 30 ends with lateral arms 46 adapted to be actuated by the cam members of a second cam shaft 47.

An exhaust manifold 48 is applied to one side of the engine, being formed with upper 40 and lower branches which communicate with the exhaust passages of both the upper and lower cylinder heads, and being held in position by suitable fastening members 49. In a similar manner the inlet manifold 50 is applied to the opposite side of the engine, being formed with upper and lower branches which extend along the upper and lower cylinder heads, and being secured in position by suitable fastening members 51. 45 The two cam shafts 29 and 47 are driven from the main shaft 8 by a suitable two to one gearing, being shown for the purpose of illustration as provided with sprocket wheels 52 which are engaged by a chain 53, 50 said chain also engaging a sprocket wheel 54 on the crank shaft. The ratio of the sprocket wheels is such that the cam shafts have a two to one motion, or make one complete revolution to each two complete revolutions of the main shaft, and the cams are arranged in such a manner as to open the inlet and exhaust valves at exactly the proper intervals of time.

The piston rods 6 are slidable through tubular guide sleeves 7 which are threaded in

the lower cylinder head 3 and project downwardly therefrom. In order to prevent leakage around the piston rods the latter are provided with annular grooves within which expansible metal packing rings 55 are fitted, 70 said packing rings being identical in construction with the conventional piston rings, and operating in an identical manner to engage the guides 7 and prevent the leakage of gases on the power stroke. 75

The upper cylinder head 2 is provided with spark plugs 56 which are arranged concentrically with respect to the cylinders, the lower spark plugs 57 extending through the sides of the cylinder at the bottom thereof, as indicated by Fig. 2. Any suitable timing and ignition system may be employed, and it will be obvious that with this construction explosions take place in both ends of the cylinders, so that with a four cycle engine 85 each piston receives a power impulse once for every revolution of the main shaft, instead of once for every two revolutions of the main shaft.

Fig. 4 is a horizontal section through one 90 of the cylinders, looking downwardly, and showing the arrangement of the four valves. The valves at the top of the cylinder are arranged in a corresponding manner, and it will be obvious that with the two inlet 95 ports and two exhaust ports at each end of the cylinder, there will be no difficulty in effectively scavenging the cylinders and introducing fresh charges into the same. In Fig. 1 the upper and lower cylinder heads 100 are shown as broken away at one end, the section being such as to extend through the exhaust passages of cylinder C and the inlet passages of cylinder A, the section taking a median line for cylinder B. 105

Having thus described the invention, what I claim as new and desire to secure by Letters Patent, is:—

1. A double acting internal combustion engine, including a cylinder, upper and lower cylinder heads closing the ends of the cylinder and each provided with inlet and outlet passages communicating with the ends of the cylinder through a plurality of ports, spring closed puppet valves controlling the 110 ports and formed with stems which project slidably through the respective cylinder heads, a pair of bracket arms projecting outwardly from each of the cylinder heads, a pair of parallel and superposed rock shafts 115 journaled between each pair of bracket arms, a plurality of fingers projecting laterally from each of the rock shafts, the fingers of one rock shaft engaging the stems of the puppet valves controlling the inlet ports 120 while the fingers of the other rock shaft engage the stems of the puppet valves controlling the exhaust ports, arms projecting from the rock shafts, and a pair of independent cam shafts having operative connections 130

with the arms of the upper and lower sets of rock shafts.

2. A double acting internal combustion engine, including a cylinder, upper and lower cylinder heads closing the ends of the cylinder and each formed with an inlet port and an exhaust port, spring closed puppet valves controlling the ports and formed with stems which project slidably through the cylinder heads, a pair of bracket arms projecting from each cylinder head, a pair of superposed rock shafts journaled between each pair of bracket arms, fingers projecting laterally from the respective rock shafts and engaging the stems of the respective inlet and exhaust valves, operating arms projecting from the rock shafts, a pair of in-

dependent cam shafts arranged at the base of the engine and extending longitudinally along opposite sides thereof, push rods connected to the arms of the upper set of rock shafts and arranged to be actuated by one cam shaft, and pull rods connected to the arms of the lower set of rock shafts and arranged to be actuated by the other cam shaft.

In testimony whereof I have signed my name to this specification in the presence of two subscribing witnesses.

JOSEPH H. DOWNS.
